UNITED STATES PATENT OFFICE.

FRANK J. BUSHEK, OF CHICAGO, ILLINOIS.

WINDOW-SHADE-ADJUSTING DEVICE.

Application filed November 26, 1926. Serial No. 150,692.

My invention relates to a window shade adjusting device, its chief object being to provide a construction of means by which to cause a window shade or curtain to be bent or bulged so as to provide an unobstructed passageway for the free movement of air through an open window.

A further object of this invention is to provide an adjustable device of this character which will embody certain desired features of simplicity, efficiency and convenience, and which is capable of operating effectively upon a conventional rolling shade.

More specifically, this invention is concerned with the provision of a rocking frame composed of angularly related shade engaging parts arranged to maintain the shade in the desired position of adjustment.

Other objects will appear hereinafter.

The invention consists in the combinations and arrangements of parts hereinafter described and claimed.

The invention will be best understood by reference to the accompanying drawings, forming a part of this specification, and in which,

Fig. 1 represents a fragmental front elevation of a window equipped with my shade adjusting device;

Fig. 2 is a vertical sectional view taken on the line 2—2 of Fig. 1;

Fig. 3 represents an enlarged detail view, with parts in section, showing in particular how the wing means are mounted for turning movement upon an axis stud;

Fig. 4 represents an elevation and a section taken on the line 4—4 of Fig. 3;

Fig. 5 represents a section and plan showing the keeper for the draw element;

Fig. 6 is a perspective view of one of the end pieces employed for connecting the wing means; and,

Fig. 7 is a perspective view of one of the bracket members.

For the purposes of illustration, I have shown the preferred embodiment of my invention in association with an ordinary window, in which 8 designates in general the window frame, 9 and 10 the upper and lower sashes, respectively, and 11 the usual window stops secured to the frame on the room side for guiding the lower sash 10. 12 denotes the customary flexible window shade and 13 the roller for the same.

In carrying out my invention, I employ a rockably mounted frame including angu-

larly connected wing means for engaging, bending and maintaining the rolling shade 12 in position to provide an unobstructed passageway through which currents of air 60 may be freely passed into or out of the room when the upper sash 9 is lowered as illustrated in Fig. 2.

The wings of my device preferably consist of two suitable wires 14 and 15, each of which has its opposite end portions bent substantially at right angles to produce leg members 16 capable of being sprung into telescoping engagement with longitudinally split tubular sockets 17, provided on end pieces 18. From an inspection of the drawings, it will be observed that each of the end pieces 18 consists of a U-shaped member and that a tubular socket 17 projects from each leg member 18' of each end piece. Each end piece is, therefore provided with two tubular sockets 17; and it will be observed (Fig. 1) that the wire wings 14 and 15, each having a leg member telescoping with a tubular socket of each end piece, constitute connections between the end pieces, thereby providing a unitary frame. Now, it is important to note here that the tubular sockets of each end piece project in angular relation so that the wire wings 14 and 15 will be held in angular relation with respect to each other as best illustrated in Fig. 2.

For the operative support of the frame, thus composed of wire wings and end pieces, two bracket elements 19 are provided, each of which consists of an elongated plate 20 carrying intermediate its length a projecting axis stud 21. The plate part 20 of each bracket is adapted to be placed flat upon a window stop 11 and to be secured thereto by means of suitable screws 22 which are passed through screw eyes 23 in the plate and then screwed into the window stop. Preferably and as shown, each axis stud 21 has an intermediate portion 24 divided by a shoulder 25 from an enlarged portion 26 and by a shoulder 27 from a threaded pin-like portion 28. Each of the end pieces 18 has a central aperture 29 adapted turnably to fit upon the intermediate portion 24; and each end piece is preferably secured in place by applying a washer 30 and securing nut 31 to the threaded portion 28, it being observed by reason of this arrangement, that each end piece is turnably mounted between a shoulder 25 and a washer 30. As best shown in Figs. 1 and 3, the end pieces are mounted upon the axis

studs so that their leg portions 18' will turn about the large portions 26 of their studs, it being observed in this connection that the tubular sockets 17 of each end piece are 5 radially related to their associated axis stud.

In use, the window shade is drawn in front of the wing 14 and behind the wing 15, as best shown in Fig. 1. By this arrangement, when the turnable frame is moved into the 10 position where the wings occupy places as shown by broken lines in Fig. 2, the window shade is permitted to depend in its customary way, but when the turnable frame is turned forwardly to occupy the position shown in 15 full lines in Fig. 2, the window shade will be engaged and bent inwardly into the room as shown at 32, thereby providing an unobstructed pasageway for the flow of air into or out of the room when the upper sash 9 is 20 lowered. For the purpose of normally maintaining the turnable frame in the position where it will not interfere with the shade 12, a sprng 33 is coiled about the portion 26 of one of the axis studs, one end of the spring 25 being engaged as at 34 with the axis stud while the other end of the spring is bent for engagement with a notch 35 provided in one of the end piece legs 18'. For limiting the movement of the turnable frame under the 30 influence of spring 33, a projection or stop 36 is provided on the bracket carrying said spring 33. A draw element or line 37 is attached at one end as at 38 to one of the upper tubular sockets, as shown in Fig. 2, for the 35 purpose of moving the frame to cause the adjustment of the window shade; and a notched keeper 39 is applied to the inside face of the window frame 8 for securing the draw line to maintain the rotatable frame 40 at the position of adjustment desired, said draw line being provided for this purpose with a series of buttons 40. By this arrangement, the window shade may be bent and maintained so as to produce a ventilating 45 passageway of the size desired at the upper part of the window, and in this connection it is to be noted that my adjusting device is so arranged that it will not interfere with the rolling of the window shade.

While I have illustrated and described the 50 preferred form of construction for carrying my invention into effect, this is capable of variation and modification without departing from the spirit of the invention. I, therefore, do not wish to be limited to the precise 55 details of construction set forth, but desire to avail myself of such variations and modifications as come within the scope of the appended claims.

Having described my invention what I 60 claim as new and desire to secure by Letters Patent is:

1. Means for adjusting a window shade comprising pivotally mounted end fittings; wing members connecting said end fittings 65 to provide for the pivotal movement of said fittings, and wing members as a unit, adapted to engage opposite sides of a window shade, and to bend it into adjusted position to produce a ventilating pasageway; means associated with said end fittings constantly urging them into one position, and means for turning said adjusting device into another position.

2. Means for adjusting a window shade 75 comprising pivotally mounted end fittings, a pair of angularly related tubular sockets carried by each of said end fittings; a pair of U-shaped wing members, each telescoping with corresponding tubular sockets of the 80 two end fittings, and adapted to engage opposite sides of a window shade and to bend it into adjusted position to produce a ventilating passageway.

3. Means for adjusting a window shade 85 comprising a pivotally mounted fitting provided with a holder extending in substantially radial relation to said fitting; a wing element adapted to said holder to be carried thereby in an arc, to cause the window shade 90 to be bent relatively to the window frame; a second wing carried by said holder and arranged to retain the lower portion of the shade parallel with the window frame.

In testimony whereof I have signed my 95 name to this specification.

FRANK J. BUSHEK.
